UNITED STATES PATENT OFFICE.

ENOS CLAYTON, OF DETROIT, MICHIGAN.

WEATHER-STRIP.

1,341,632.

Specification of Letters Patent.

Patented June 1, 1920.

Application filed August 9, 1919. Serial No. 316,375.

To all whom it may concern:

Be it known that I, ENOS CLAYTON, a citizen of the United States, residing at Detroit, county of Wayne, State of Michigan, have 5 invented a certain new and useful Improvement in Weather-Strips, and declare the following to be a full, clear, and exact description of the same, such as will enable others skilled in the art to which it pertains 10 to make and use the same, reference being had to the accompanying drawings, which form a part of this specification.

My invention relates to weather strips and particularly to a weather strip designed for 15 use in connection with the sill and lower cross rail in a casement or hinged window, commonly spoken of as a "French" window, or a sash door.

In the drawings:

20 Figure 1 is a perspective in section showing the casement window hinged in place.

Fig. 2 is a sectional view showing the cross rail of the window slightly withdrawn from its seat.

25 Fig. 3 is a modification of the weather strip provided with the sill.

In the drawings let *a* represent the jamb of a casement window; *b* the sash swung from such jamb; *c* the window sill, and *d* the outer stop or sub-sill embedded therein. 30 *e* is the lower cross rail of the window which abuts the outer stop when the window is closed.

The lower rail *e* is recessed in rectangular 35 cross-section so that a portion of it overlaps the outer stop and weather strip carried by the sill. A vertical groove *e*² extending upward from said recess and adapted to receive the weather strip *f*, which is bent outwardly 40 within the said recess forming a horizontally dependent flange extending flush with the outer surface of the lower cross rail, is provided. To the sill is attached a weather strip *g*, as shown, comprising a base portion 45 *g*² which is adapted to be fastened to the sill by means of screws or nails and extends outwardly thereon. Such base portion is provided with a trough, the outer side of which is substantially vertical, the inner side 50 being formed to follow the outer curvature of the outer stop *d* and projects interiorly thereof. Both sides have their upper edges turned inwardly forming horizontal flanges *g*³, *g*⁴ spaced one from the other. The space 55 provided between the horizontal inwardly projecting flanges *g*³ and *g*⁴ is adapted to re-

ceive the outwardly-projecting horizontal flange *f*² of the coöperating strip carried by the cross rail of the window. This forms a weather-tight joint between sections *f* and *g* 60 of the weather strip. The flange *g*⁴ is adapted to fit into a horizontal groove *e*³ in the lower cross rail. Said horizontal groove *e*³ extends inwardly from the inner face of the recess in said cross rail and is flush with 65 the under surface of the outwardly-projecting flange *f*². The trough is further provided with openings *h*, *h*, allowing the water which may collect therein to flow outward through such openings on the slope of the 70 sill.

It will be noted that a peculiarly well-designed weather strip is here provided for the purpose sought. Any water which may blow through between the flange *g*³ and the 75 lower cross rail *e* would not fall interior of the outer stop on the sill and be in position to seep through underneath the window, but would be caught by the horizontal outwardly projecting flange *f*² of the coöperating 80 section of the weather strip carried by the window and drain back into the trough and out through the openings *h* provided therein. Any moisture following the metal weather strip *f*² out underneath the same, 85 eventually dripping off from the underside, would be caught by the interiorly projecting flange *g*³ and drain back into the trough.

Fig. 2 shows the weather strip *g* made of one piece of metal. Fig. 3 is a modification 90 thereof showing the weather strip *g* made of two pieces of metal, the lower piece forming the inside wall of the trough, the outer one forming the outside wall thereof. The operation would in each instance be similar. 95

What I claim is:

1. In a casement window, in combination with a window frame provided with a sill and outer stop affixed thereto, the lower cross-rail of said window recessed to overhang said outer stop, a weather-strip carried by said cross-rail dependent within said recess and provided with an outwardly projecting horizontal flange spaced from the ceiling of said recess, a coöperating weather-strip carried by the sill comprising a trough provided with inwardly projecting horizontal flanges spaced one from the other adapted to receive between them in close-fitting relationship the outwardly-projecting horizontal flange of the weather-strip carried by the cross-rail. 105 110

2. In a casement window, in combination with a window frame provided with a sill and sub-sill fastened thereto, the lower cross-rail of said window recessed to abut and overhang the outer stop of the sill and provided with an inwardly-extending, horizontal groove, a weather-strip carried by said cross-rail dependent in said recess provided with a horizontal outwardly-projecting flange spaced from the ceiling of said recess, a coöperating weather-strip carried by the sill comprising a trough with upright sides which sides are bent inwardly forming horizontal flanges spaced one from the other adapted to receive between them the outwardly-projecting flange of the weather strip carried by the sash and to be received, the one within the groove formed between the outwardly-projecting flange of the strip carried by the sash and the ceiling of the recess within which it depends, the other within the inwardly extending groove formed in the cross-rail.

3. In a casement window, the combination with a window frame provided with a sill and sub-sill, a lower cross-rail of said casement window recessed to overhang the sill and sub-sill, a weather strip carried by said cross-rail dependent within said recess and provided with a horizontal outwardly-projecting tongue spaced from the ceiling of said recess, said cross-rail provided with a horizontal groove extending inwardly of said recess, the ceiling of said groove flush with the under surface of said outwardly-projecting tongue, a coöperating weather strip carried by the sill comprising a trough one side of which is bent to follow the curvature of the sub-sill, the other and outer side projecting upwardly, both sides being bent inwardly forming horizontal flanges spaced one from the other, adapted to receive between them in close fitting relationship the outwardly-projecting horizontal flange of the portion carried by the window sash, the inwardly-projecting flanges of the strip carried by the sill adapted to be received the one within the horizontal groove in the cross-rail, the other within the space provided between the outwardly-projecting flange of the weather strip carried by the cross-rail and the ceiling of the recess in said cross-rail.

4. In a casement window, in combination with a window frame provided with a sill and sub-sill *d*, a lower cross-rail recessed at the outer lower edge to overhang the sill and said sub-sill and provided with a horizontal groove extending inwardly from said recess, a weather strip carried by said cross-rail dependent within said recess and bent outwardly at right angles forming a horizontal flange projecting outwardly flush with the outer vertical surface of the cross-

rail and spaced from the ceiling of said recess, a weather strip fashioned to form a trough carried by said sill adjacent the outer surface of said sub-sill, one of the walls thereof following the curvature of said sub-sill and projecting in the form of a horizontal flange interiorly thereof, said flange adapted to be received in the horizontal groove of said cross-rail, the outer wall of said trough projecting upwardly beyond said inner wall then turning inwardly forming a second horizontal flange spaced from said lower horizontal flange, the space therebetween adapted to receive the outwardly-projecting flange of the strip carried by the cross-rail, said upper inwardly-projecting flange adapted to be received between the outwardly-projecting flange and the ceiling of the recess, the outer wall of said trough perforated to permit the flow of water therethrough.

5. In a casement window, in combination with a window frame provided with a sill and outer stop of a lower cross-rail recessed at its lower outer edge to abut and overhang the outer stop carried by the sill and provided with a horizontal groove extending inwardly from said recess, a weather strip fashioned in the form of a trough with the two sides thereof terminating in horizontal flanges bent inwardly, spaced one from the other, the lower of said flanges adapted to be received within said inwardly-extending groove in the cross-rail, a weather-strip carried by the cross-rail provided with an outwardly-projecting flange spaced from the ceiling of the recess, said spaced opening adapted to receive the upper of said inwardly-projecting flanges of the trough, said outwardly-projecting flange of the strip carried by the cross-rail adapted to be received between the inwardly-projecting flanges of the strip carried by the ceiling.

6. In a casement window, a window frame provided with a sill, a weather strip fashioned to form a trough the sides of which extend upwardly and then turn inwardly forming horizontal flanges spaced one from the other carried by said sill, the lower cross-rail of said window recessed to abut and overhang said inwardly-projecting flanges and provided with two horizontal grooves to receive the same, one of said horizontal grooves being cut into said cross-rail, a weather strip dependent within said recess provided with an outwardly-projecting horizontal tongue spaced from the ceiling of said recess so as to form the other horizontal groove.

In testimony whereof I sign this specification.

ENOS CLAYTON.
